UNITED STATES PATENT OFFICE.

ALBERT PRIESTMAN, OF PHILADELPHIA, PENNSYLVANIA.

AIR-FLUSHING APPARATUS.

1,048,206.

Specification of Letters Patent. Patented Dec. 24, 1912.

Application filed April 17, 1911, Serial No. 621,488. Renewed November 9, 1912. Serial No. 730,499.

To all whom it may concern:

Be it known that I, ALBERT PRIESTMAN, a subject of the King of England, and a resident of the city and county of Philadelphia, State of Pennsylvania, have invented an Improvement in Air-Flushing Apparatus, of which the following is a specification.

In the application of Hubert Beddoes, Ser. No. 540,432, filed January 27, 1910, is described an apparatus for flushing air in which, upon the accumulation of sufficient head acting upon a hydrostatically controlled pressure accumulator, such as an air-bell, a liquid seal is forced in a pipe leading from the accumulator, and a charge of air rushes through the air pipe into an accumulator, from which it may pass to air controlled devices. By this means a sufficient volume of air may be flushed from a single 15 hydrostatically controlled accumulator on each operation to operate several separate and independent devices, the surplus air passing from one device to the next. The flushing of the air takes place each time the 20 liquid in the vessel in which the accumulator is placed attains sufficient head to force the liquid-seal in the pipe leading to the receiver. In many cases, however, it is desirable that the air should be flushed only 25 at intervals with reference to the rise and fall of the liquid in the controlling tank. For example, it may be desirable that certain air controlled devices, such as air locks, should be operated only once in twenty four 30 hours, while the controlling tank should be filled and emptied hourly.

It is one of the objects of the present invention to accomplish this result; and this I do by interposing, between the hydrostatically controlled bell and the receiver, a pressure-accumulator having a larger capacity than the hydrostatically controlled bell. The water sealed air pipe from the hydrostatically controlled bell leads to this large 45 accumulator, and from it a water sealed air pipe leads to the receiver. On each operation of the hydrostatically controlled bell air is forced into the large accumulator, but the air is not flushed therefrom until sufficient 50 pressure is accumulated by successive operation of the hydrostatically controlled bell to force the seal in the pipe leading to the receiver.

It is also an object of the invention to enable a large charge of air to operate suc-

sively upon air controlled devices. Thus the amount of air flushed once a day, may be made to operate air controlled devices hourly.

By my apparatus successive air flushing operations at short intervals may be used to flush a relative large quantity of air at long intervals, and this large quantity of air thus flushed may be made to again successively flush small quantities of air at short intervals.

In the drawings: Figure 1 is a vertical sectional view of a hydrostatically controlled air-flushing device embodying the invention; and Fig. 2 is a similar view illustrating that form of the apparatus in which the air is flushed intermittently from the receiver.

a is the hydrostatically controlled air-bell submerged in the liquid in the tank or bed *b*, in which the level of the liquid rises and falls.

g is the relatively large accumulator submerged in liquid in the chamber *m*.

e is an air-pipe leading from the bell *a* and having an upturned end *e'* forming a water-seal leading into the accumulator *g*.

c is an air-bell, relatively small with reference to the accumulator *g* submerged in liquid in the chamber *d*.

h is an air-pipe leading from the accumulator and having an upturned end *h'* forming a water-seal leading into the bell *c*.

f is the discharge pipe from the bell or receiver *c* which may lead to any air controlled devices. In the apparatus shown in Fig. 2 this pipe *f* terminates in a water seal *f'* opening into a small bell *i* submerged in liquid in the tank *n*, and from this bell *i* a discharge pipe *j* leads to air controlled devices. In this apparatus the pipe *h* leading from the accumulator *g* to the air-bell *c* is provided with a throttling valve *k*.

When the liquid reaches a sufficient level to force the water seal *e'* in the pipe *e*, a charge of air will be forced from the bell *a* into the accumulator *g*. Owing to the greater size of the accumulator *g* and the strength of the seal *h'*, this charge of air will not be sufficient to force the seal *h'* and discharge air into the bell *c*. The operation will, therefore, be repeated each time the liquid in *b* attains the necessary head, until sufficient pressure is accumulated in the accumulator *g* to force the seal *h'*. The air will then rush from the accumulator *g* into the receiver *c* and will pass thence

through the pipe *f* to the air controlled devices. By properly proportioning the bell *a* and accumulator *g* this flushing of the air may take place at predetermined intervals 5 with reference to the rise and fall of the liquid in the tank *b*.

In the form of the apparatus shown in Fig. 1, when the seal *h'* is forced by the accumulated pressure in the accumulator *g*, 10 the entire charge of air will rush into the receiver *c* and pass thence through the pipe *f*. In the form of the apparatus shown in Fig. 2, however, the flow of the air from the accumulator *g* into the receiver *c* may be regulated 15 by the adjustment of the valve *k*, and as soon as the pressure in the receiver *c* is sufficient to force the seal *f'* a relatively small charge of air will pass through the pipe *f* into the bell *i* and thence through the 20 pipe *j*, so that just as successive operations of the bell *a* may be used to produce each operation of the accumulator *g*, each operation of *g* may be made to produce successive 25 operations of the bell *i*.

25 What I claim is as follows:

1. In apparatus for the purpose described, the combination of an air-pipe having a liquid-seal, a hydrostatically controlled air-bell communicating with said air-pipe, a 30 sealed pressure accumulator of larger size than said hydrostatically controlled air bell inclosing the liquid seal of said air pipe, an air-pipe leading from said accumulator and having a liquid seal, a sealed receiver inclosing 35 the liquid seal of the air-pipe leading from said accumulator, and a delivery pipe for the flushed air leading from the receiver.

2. In apparatus for the purpose described, 40 the combination of a hydrostatically controlled air-bell, a sealed pressure accumulator of larger size than said air-bell, a sealed receiver, an air-pipe leading from the air-bell to the accumulator and having a liquid seal, an air-pipe leading from the 45 accumulator to the receiver and provided with a liquid seal, and an air-discharge pipe from the receiver.

3. In apparatus for the purpose described, 50 the combination of a hydrostatically controlled air-bell, a sealed pressure accumulator of larger size than said air-bell, a sealed receiver, an air-pipe leading from the air-bell to the accumulator and having a liquid seal, an air-pipe leading from the 55 accumulator to the receiver and provided with a liquid seal, means to control at will the flow of the air from the accumulator to the receiver, and an air-discharge pipe from the 60 receiver.

4. In apparatus for the purpose described, 65 the combination of a hydrostatically controlled air-bell, a sealed pressure accumulator of larger size than said air-bell, a sealed receiver, an air-pipe leading from the air-

bell to the accumulator and having a liquid seal, an air-pipe leading from the accumulator to the receiver and provided with a liquid seal, a valve in said pipe, and an air-discharge pipe from the receiver.

5. In apparatus for the purpose described, 70 the combination of a hydrostatically controlled air-bell, a sealed pressure accumulator of larger size than said air-bell, a sealed receiver, an air-pipe leading from the air-bell to the accumulator and having a liquid seal, an air-pipe leading from the accumulator to the receiver and provided with a liquid seal, an air-discharge pipe from the receiver having a liquid-seal, and an air-bell 75 of smaller size than the accumulator inclosing said liquid-seal in the air-discharge pipe from the receiver.

6. In apparatus for the purpose described, 80 the combination of a hydrostatically controlled air-bell, a sealed pressure accumulator of larger size than said air-bell, a sealed receiver, an air-pipe leading from the air-bell to the accumulator and having a liquid seal, an air-pipe leading from the accumulator to the receiver and provided with a liquid seal, an air-discharge pipe from the receiver having a liquid-seal, an air-bell 85 of smaller size than the accumulator inclosing said liquid-seal in the air-discharge pipe from the receiver, and means to control at 90 will the flow of the air from the accumulator to the receiver.

7. In apparatus for the purpose described, 95 the combination of a hydrostatically controlled air-bell, a sealed pressure accumulator of larger size than said air-bell, a sealed receiver, an air-pipe leading from the air-bell to the accumulator and having a liquid seal, an air-pipe leading from the accumulator to the receiver and provided with a liquid seal, a valve in said pipe, an air-discharge pipe from the receiver having a liquid seal, and an air-bell of smaller size than the accumulator inclosing 100 said liquid-seal in the air-discharge pipe from the receiver, and means to control at will the flow of the air from the accumulator to the receiver.

8. In apparatus for the purpose described, 105 the combination of a sealed pressure accumulator, a sealed receiver, an air-pipe leading from the accumulator to the receiver and having a liquid-seal, an air-bell of smaller size than the accumulator having a discharge-pipe, an air-pipe leading from the receiver to the air-bell and having a liquid-seal, and means to control at will the flow of the air from the accumulator to the receiver.

9. In apparatus for the purpose described, 115 the combination of a sealed pressure accumulator, a sealed air-bell of relatively smaller size than the accumulator, an air-pipe having a liquid seal leading from the accumulator and adapted to supply air therefrom to the air-bell, and means to con- 120

trol at will the flow of the air through said air-pipe.

10. In apparatus for the purpose described, the combination of a sealed pressure 5 accumulator, a sealed air-bell of relatively smaller size than the accumulator, an air-pipe having a liquid seal leading from the accumulator and adapted to supply air therefrom to the air-bell, and a valve to con-

trol at will the flow of the air through said 10 air-pipe.

In testimony of which invention, I hereunto set my hand.

ALBERT PRIESTMAN.
